UNITED STATES PATENT OFFICE.

HARRY ALLCARD, OF SHEFFIELD, ENGLAND.

DESIGN FOR A HEAD FOR LIFTING-JACKS.

SPECIFICATION forming part of Design No. 23,475, dated July 17, 1894.

Application filed January 9, 1894. Serial No. 496,322. Term of patent 3½ years.

To all whom it may concern:

Be it known that I, HARRY ALLCARD, manufacturer, a subject of the Queen of Great Britain, and a resident of Sheffield, in the county of York, England, have invented and produced an original Design for the Head of a Lifting-Jack, of which the following is a specification.

In the drawing the figure is an elevation of the jack.

The leading feature of my design is the configuration of the head A, with the projecting perforated eyes on each side. This head has a cylindrical end which curves inwardly to a reduced inner end and this reduced extension has eyes E D projecting from the periphery on

each side of the tapered portion of the head. The reduced end terminates in a squared portion.

I claim—

The design for the head of a jack herein shown and described.

In testimony that I claim the foregoing as my own I have affixed hereto my signature, in presence of two witnesses, this 26th day of October, 1893.

HARRY ALLCARD.

Witnesses:

ROBERT F. DRURY,
BERNARD E. DRURY.
